UNITED STATES PATENT OFFICE.

LYMAN P. ERNST, OF DES MOINES, IOWA.

TRAFFIC-SIGNAL CONTROL.

1,317,009.

Specification of Letters Patent. Patented Sept. 23, 1919.

Application filed January 28, 1919. Serial No. 273,665.

To all whom it may concern:

Be it known that I, LYMAN P. ERNST, a citizen of the United States, and a resident of Des Moines, in the county of Polk and State of Iowa, have invented a certain new and useful Traffic-Signal Control, of which the following is a specification.

The object of my invention is to provide a traffic signal control of simple, durable and inexpensive construction.

More particularly it is my object to provide such a device located at a crossing above the path of traffic, and having means located out of the path of traffic for controlling said device.

With these and other objects in view my invention consists in the construction, arrangement and combination of the various parts of the device, whereby the objects contemplated are attained, as hereinafter more fully set forth, pointed out in my claim and illustrated in the accompanying drawings in which:

Figure 1 shows a front elevation of a signal traffic control embodying my invention.

Fig. 2 shows a top or plan view of part of the device.

Fig. 3 shows a horizontal, sectional view taken on the line 3—3 of Fig. 1.

Fig. 4 shows a side elevation of the signal device proper taken at right-angles to the view shown in Fig. 1.

Fig. 5 shows a top or plan view of a portion of the device.

Fig. 6 shows a vertical, sectional view taken on the line 6—6 of Fig. 5 part of the device being omitted.

My device is intended to be used as a traffic signal on street intersections.

The device includes two upright supporting members indicated in the accompanying drawings by the reference characters 10 and 11, and preferably located respectively on the northwest and southeast corners of the intersection, out of the way of traffic.

Extending between the upper portions of the uprights 11 is a supporting wire or the like 12, the central portion of which is supported by brace wires 13.

I provide a collar 14 having oppositely extended arms 15 preferably terminating in loops 16.

The loops 16 are fastened to the wire 12 by means of wires 17 or in any suitable way.

Supported by the collar 14 is a bearing member 18 having an external, annular

groove in which the collar 14 is received for rotatably supporting the bearing member 18.

The bearing member 18 has a central, vertical angular opening 19 extending 60 through it.

Slidably but non-rotatably received in the opening 19 is an upright signal supporting member 20 having on its upper end a collar 21, which prevents the supporting member 20 from drooping downwardly through the bearing member 18.

Supported on the lower end of the signal supporting member 20 are boards or the like 22 arranged at right-angles with relation to 70 each other. One of the boards has printed or otherwise marked on its opposite faces a suitable word such as the word "Proceed", and the other of said boards or the like has printed or otherwise marked on its opposite 75 faces a suitable word such as the word "Stop", as indicated respectively in Figs. 1 and 4.

Supported just below the board 22 is a receptacle 23 which should have transparent 80 walls of suitable colors.

Extending laterally from the bearing member 18, preferably at a ninety degree angle with relation to each other are arms 24 and 25.

Suitably mounted on the upright 10 preferably on the northwest corner of the intersection, for better protection, is a cage or small house 26 for the traffic officer, which may have a top 27 and transparent windows 90 or walls 28.

Rotatably mounted in suitable bearings on the cage 26 is an upright shaft 29, on which is a controlling handle 30. On the upper end of the shaft 29 are arms 31 and 95 32 preferably arranged at an angle of ninety degrees with relation to each other.

The arms 31 and 32 are pivoted to links 33 and 34 respectively. The links 33 and 34 are pivoted to the respective arms 24 and 25.

Secured to one of the boards or the like 22 is a cable or rope 35, which extends upwardly over a pulley 36 on the bearing member 18, and thence over a pulley 37, and thence to the cage 26 where it may be detachably secured to a suitable fastening device 38.

In the receptacle 23 is an electric light 39 which may be connected by wires 40 with a suitable source of electric energy.

One of the wires 40 connects with a switch 41 in the cage 26.

On the support 10 may be provided ladder steps 42 for permitting easy access to the cage 26 by the traffic officer.

In the practical use of my improved traffic signal device, the device is installed in the manner hereinbefore mentioned.

The traffic officer can, by means of the lever handle 30, rotate the shaft 29 for there-by operating the links 33 and 34 for im-parting rotation to the bearing device 18 and the signal supporting member 20.

He can then cause the board having the word "Proceed" or its equivalent thereof, to be opposite one street, and the other board 15 to be opposite another street, and can then, when he desires, impart a quarter turn to the signal for giving the proper signals to the traffic.

When the traffic officer leaves the cage 26 20 he may, by means of the loop or cable 35, pull up the signal device to its position shown by dotted line in Fig. 1, which will indicate to the traffic that no officer is on duty.

It will be obvious that the signal boards 25 will at all times be high enough not to interfere with the traffic.

In the day time the signal boards can be plainly seen, and at night the light will give 30 the desired signal.

The signal boards may be raised or lowered as desired for indicating that the signal is in use, and yet the signal boards can be rotated a quarter turn when desired.

The officer will be high enough so that 35 he can see the traffic much better than when standing in the middle of the street. He will be sheltered from the weather, and will be free from danger of injury which exists 40 when he stands in the street.

The signal is easier to see than the waving arms of the officer, for the reason that it is higher than the officer would be standing in 45 the street.

It is also much easier for pedestrians on

the sidewalk to see, and thus makes for the safety of pedestrians.

The entire device is not expensive and is of simple construction, and after installation the device may be used indefinitely. 50

The light on the signal may be controlled from the officer's cage.

The "proceed" board or the like is preferably colored green with distinctly colored letters and the corresponding transparent 55 walls of the receptacle 23 are also preferably green, while the "stop" board and the corresponding receptacle walls are preferably red.

The cage may have a seat and heating 60 means if desired.

My device greatly reduces the strain on the traffic officer and enables him to work longer hours without relief.

Some changes may be made in the construction and arrangement of the various parts of my improved signal device without departing from the essential features and purposes of my invention, and it is my intention to cover by my claim any modified 65 forms of structure or use of mechanical equivalents which may be reasonably included within their scope.

I claim as my invention:

A traffic signal device comprising spaced 75 supports, a supporting wire mounted on said supports, a supporting member rotatably mounted with relation to said wire, a signal supporting device on said member mounted to rotate with said member and to slide vertically with relation thereto, a signal device on the lower end of said signal supporting device, means for raising and lowering said signal supporting device, and means for im-parting limited rotation to said supporting 80 member for rotating said signal device in any of its vertically adjusted positions.

Des Moines, Iowa, January 18, 1919.

LYMAN P. ERNST.
